UNITED STATES PATENT OFFICE

JOSEPH MURASCO, OF SANDUSKY, OHIO, ASSIGNOR TO THE MADE-RITE
MANUFACTURING CO., OF SANDUSKY, OHIO, A CORPORATION OF OHIO

DESIGN FOR A STAND FOR DRINK MIXING DEVICES

Application filed February 21, 1931. Serial No. 38,768. Term of patent 7 years.

To all whom it may concern:

Be it known that I, JOSEPH MURASCO, a citizen of the United States, residing at Sandusky, in the county of Erie and State of Ohio, have invented a new, original, and ornamental Design for a Stand for Drink Mixing Devices, of which the following is a specification, reference being had to the accompanying drawing, forming a part thereof, wherein,

I claim:

The ornamental design for a stand for drink mixing devices, as shown.

JOSEPH MURASCO.
